VENDING MACHINE FOR FROZEN
PRODUCTSCharles J. Porter, Glenolden, Pa., assignor of one-
half to Howard Davis, Philadelphia, Pa.

Application November 3, 1934, Serial No. 751,292

4 Claims. (Cl. 194—85)

My invention relates to new and useful improvements in a vending machine for frozen products and has for one of its objects to provide means for controlling the temperature between the refrigerant bunker and the package containers.

The machine is particularly adapted for vending packages of ice cream which must be maintained in a solid or firm condition but not so hard that they cannot be eaten readily as soon as delivered. Therefore another object of the invention is to provide means for regulating the transfer or exchange of heat units between the package containers and the refrigerant bunker.

The machine is especially designed to use dry ice as the refrigerant which produces an exceedingly low temperature and it is necessary to control this temperature in a simple efficient manner without waste, wherefore an object of the present invention is to utilize means not only to regulate the exchange of heat, but also to conserve the refrigerant or cooling medium.

Another object of the invention is to construct a machine of this kind to be placed in condition for operation by the insertion of a coin of proper denomination or the equivalent thereof, the mechanism being capable of one single complete actuation for each inserted coin.

Another object of the invention is to provide a coin control mechanism which functions upon the insertion of a proper coin providing there is merchandise to be dispensed and which will prevent repeats as well as prevent the delivery of goods for improper coins or slugs although a proper coin will be returned if there is no goods to be delivered.

Another object of the invention is to provide an arrangement of parts so associated that the refrigerant bunker functions as an absorbing chamber, for taking up the heat units in the other elements of the machine and the merchandise therein, in contradistinction to the usual method of circulating chilled air about the frozen merchandise.

Another object of the invention is to locate fins in certain positions to assist in quickly absorbing or transferring excess heat units from the merchandise or package containers to the refrigerant bunker or absorbing chamber.

A further object of the invention is to provide removable racks to hold the packages of merchandise whereby a new supply may be readily and quickly placed in the machine.

A still further object of the invention is to provide a unique form of door or closure for the

delivery end of each merchandise container which is quickly but quietly closed as soon as the merchandise is delivered.

With these and other objects in view this invention consists of the details of construction and combination of elements hereinafter set forth and then specifically designated by the claims.

In order that those skilled in the art to which this invention appertains may understand how to make and use the same, I will describe its construction in detail referring by numerals to the accompanying drawings, in which:—

Fig. 1 is a front elevation of a vending machine constructed in accordance with my invention and having parts of the upper portion broken away and shown in section to illustrate certain details of the structure.

Fig. 2 is a side elevation thereof having parts of the upper portion broken away to show the locations of some of the elements.

Fig. 3 is an enlarged fragmentary front elevation with the front closure of the casing removed.

Fig. 4 is a further enlarged view on the line 4—4 of Fig. 3, with the parts in closed positions.

Fig. 5 is a perspective view of a section of the paper shield which is used to control or regulate the absorption of heat units by the refrigerant, edges of the shield sheets being separated to illustrate the construction.

Fig. 6 is a side elevation of one of the package delivery chutes showing the control means for the barrier and coin deflector.

Fig. 7 is a view similar to Fig. 4, on a larger scale and showing the parts in a full open position.

Fig. 8 is a detail sectional view of one of the coin pockets, showing the deflector in its normal position for the return of coins.

Fig. 9 is a front edge view of said coin pocket.

Fig. 10 is a side elevation of one of the bottom refrigerator plugs or closures with attached extractor, one of the arms of the latter being broken away to illustrate connection of fingers.

Fig. 11 is a plan view of the inner ends of the extractor arms with attached fingers.

Fig. 12 is a perspective view of one of the package guides and holders.

Fig. 13 is a fragmentary view partly in elevation and partly in section of one of the coin selectors which with a coin functions as a clutch to connect a delivery mechanism with the operating mechanism.

Fig. 14 is a front elevation of Fig. 13.

55

Fig. 15 is a section on the line 15—15 of Fig. 1. In carrying out my invention as herein embodied, 20 represents the casing or cabinet closed at the top by a lid 21 and having a doorway 22 in its front wall which is normally closed by a removable door 23 provided with a lock 24.

A large can 25 is located in the upper rear part of the casing or cabinet and in spaced relation to the walls of said cabinet whereby suitable insulation 26 may be installed to properly insulate the cooling compartment produced by said large can. This large can 25 is open at the front but has the forward edges of its end walls attached to a vertical plate or partition 27 extending from one side to the other of the interior of the insulated upper part of the casing.

Within the said large can 25 are located a number of small cans 28 which are also open at the front and are fixed to the vertical plate or partition 27 by means of the edges of their side walls, and the back walls and bottoms of said small cans are spaced from the contiguous walls of the large can to provide air circulating spaces. Further the small cans are spaced from each other laterally as will be obvious by reference to Fig. 15, to provide air circulating passageways between said small cans.

At the bottom of each small can in the front thereof is left a package outlet opening 29 through which the packages are to be delivered and from this outlet opening leads an inclined sill 30.

A package carrying rack 31 is removably mounted in each small can and comprises three upright channel bars 32 connected to U-shaped struts 33 with a foot 34 at the bottom of the rack, said foot carrying a lug 35 for registration with a hole in the bottom of the small can when the forward end of the foot is projected into the outlet opening 29. It is to be understood that the smaller cans have enough space between their front and back wall to permit the racks to be moved backward to withdraw the feet from the openings and then lift the racks out through the tops of said small cans.

Each channel bar has two guides 36 of suitable material that will not collect frost, such as "Bakelite" so that packages of frozen merchandise will not stick to the racks. In the region of each rack within each small can are two guides 37 of the same material as the guides 36 mounted on the plate or partition 27 so that when a rack is in place, a storage space is produced to hold the packages in position for vending.

At the upper end of the casing or cabinet between the plate or partition 27 and the front wall of said casing or cabinet is located the refrigerant bunker 38 having a sloping bottom wall 39 inclined downwardly toward said plate or partition 27. This bunker is adapted to contain a suitable refrigerant 40, Fig. 2, preferably "dry ice" or an equivalent, and in order to control or regulate the low temperature thereof or the exchange of heat units between the refrigerant bunker and the merchandise storage chambers or the packages of merchandise therein, I locate a number of shields 41 on the inside of the ice bunker against the wall next to the plate or partition 27.

These shields are formed from two layers 42 of thirty pound paper with a layer 43 of fifteen pounds asphaltum between them and they are arranged in the refrigerant bunker so that they overlap one another in shingle fashion with a

single thickness at the lower end of the bunker. The shields are assembled so that they can be adjusted vertically whereby additional thicknesses can be placed at the lower end of the bunker when desired, as in very cold weather and the majority or all of them can be moved to the upper end of the bunker in hot weather thereby permitting a greater absorption of heat units from the merchandise storage compartments. This is very important when "dry ice" is used because of its low temperature and it is a well known fact that if frozen products, such as ice cream, are maintained in an extra solid condition, they cannot be eaten immediately upon being dispensed and the flavor is not of the desired quality. With my means for and method of controlling the exchange of heat units, the ice cream will be maintained sufficiently hard and firm to keep it in good condition and yet relatively soft so that it can be eaten at once. Ice cream in this form is palatable and has a true flavor. The use of the shields also conserves the refrigerant because of the low conductivity of said shields.

Particular attention is called to the location of the refrigerant bunker which is at the upper ends of the merchandise compartments and the shields are positioned so that the greatest exchange of heat units will take place at the bottom of the bunker thereby evenly distributing the temperature from top to bottom of the containers.

An operating shaft 44 extends across the interior of the casing or cabinet below the insulated parts of the machine, with one end projecting through one of the side walls of said casing. On the projecting end is mounted and fixed a handle 45, and in order to return said handle, its shaft and other parts to their normal "rest" positions, I provide a spring 46, which may be housed in the handle, having one end anchored to a stationary element, such as the casing of the machine or a ferrule 47 fixed to the casing and the other end connected to the handle. The operating shaft 44 is journalled in main bearing hangers 48 secured to a horizontal support plate 49 located below the refrigerator and extending completely across the casing and from the back thereof to position short of the casing front so as to be spaced therefrom.

On the operating shaft in the region of each merchandise compartment is mounted an idler pinion 50 urged in a reverse direction by a spring check 51 including a cylinder 52 having one end secured to a bracket or hanger 53 attached to the supporting plate 49. At the lower end of the cylinder is a screw 54 for regulating the passage of air to and from the cylinder to control the action of the spring check. Within the cylinder is slidably mounted a piston 55 carried by the piston rod 56 extending through the upper end of the cylinder, which is closed except for a hole through which a piston rod projects. A coupling or link 57 is attached to the projecting end of the piston rod and pivoted at 58 to the idler pinion 50. A coil spring 59 surrounds the piston rod with one end engaging the upper end of the cylinder, as the stationary element, and the other end engaging the piston, as the movable element.

This idler pinion 50 meshes with a gear rack 60 slidably mounted in a rack guide 61 secured to the supporting plate 49. On the forward or outer end of the gear rack 60 is secured a closure plug supporting bracket 62 for carrying the

closure plug 63 and the associated package extractor 64. The closure plug 63 is designed to fit into the outlet opening 29 and carries a gasket 65 to engage the faces of the walls surrounding the outlet opening to seal the latter and make the package compartment air tight at the bottom.

The closure plug 63 carries a plate 66 from which projects a threaded trunnion 67, Fig. 10, for passage through a hole in the upper end of the bracket 62 whereby said closure plug is hung on the bracket and the parts are held together by a nut 68 screwed onto the trunnion. In order to adjust the closure plug on the bracket 15 so that said closure plug will properly enter the outlet opening 29 and the gasket 65 properly seal said outlet opening even though there be some discrepancies in aligning the parts during manufacture, a number of set screws 69 are threaded through the bracket 62, about the hole receiving the trunnion, with their inner ends impinging on the plate 66. This enables the party assembling the machine to mount the plug closure in a horizontal plane parallel with the bracket or in any canted position relative to said bracket.

The extractor 64 is mounted on the closure plug 63 and projects from the inner face thereof through the outlet opening 29 into a small can 28 or package compartment. The extractor includes two arms 70, each having an inwardly projecting lug 71 on which is mounted a spring actuated finger 72 so as to normally stand in a substantially upright position but capable of being pushed down as they pass beneath a stack of merchandise packages. The arms 70 of the extractor are preferably positioned so as to pass under the lower ends of the upright bars 32 of the package carrying rack 31 at both sides of the foot 34 and are long enough to reach beyond the back of the package carrying rack whereby the spring actuated fingers 72 can straighten up after passing the rear edge of a package resting on the foot 34 of said package carrying rack. With the fingers back of the package which is below the top of the outlet opening 29, said package can be drawn through the outlet opening when the extractor is moved forwardly as will be more fully described below.

Each idler pinion 50 has a coin retainer 73 fixed thereto and as illustrated in Figs. 13 and 14, said coin retainer includes a rear plate 74 having a recess 75 formed longitudinally therethrough open at both ends as well as at one side. The depth of this recess is equal to the thickness of the coin 76 which is to cause the machine to function and the side wall of said recess is flared toward the entrance as at 77 and also has a notch to form a stop shoulder 78 which will arrest the proper coin but permit smaller ones or slugs to pass through the recess and out of its lower end. The recess 75 is partially closed by a front plate 79 which, with the rear plate, is secured to the idler pinion by screws 80 or equivalent fastening means.

The idler pinion 50 has a side flange 81 projecting from one side thereof which is as wide as the coin retainer 73, or approximately so, and its outer perimeter is flush with the upper end of said coin retainer and said flange 81 functions as coin arrester as will be apparent from the later description.

A driving element 82 is fixed to the operating shaft 44 beside each idler pinion with which it co-operates. This driving element includes a

flat segment 83 which lies in very close proximity to the side edge of the flange 81 preferably without actually touching said flange. A portion of the flat segment projects across the open side of the coin retainer 73 and thereby closes 5 the other side of the recess 75 in said coin retainer.

All of the flat segments 83 of the several driving elements 82 are shown as ratchets but only one of these constitutes a ratchet which, by 10 preference, is the one adjacent the operating handle 45. In the course of manufacture it is easier to make all of the flat segments alike rather than make one as a ratchet and all the others as plates.

The flat segment which is to function as a ratchet, must have ratchet teeth 84 for co-action with a pawl 85 pivoted in the pawl bearing 86 secured to the supporting plate 49. This pawl and ratchet prevents a reverse movement 15 of the handle and any of the driving elements until a complete forward movement has been accomplished. A notch 87 is formed in the edge of the segment forward of the ratchet teeth and another notch 88 is similarly produced to the rear 25 of the ratchet teeth. These notches are for reversing the pawl at the end of each oscillation of the ratchet segment. As shown in Fig. 4, the ratchet segment is in its full return position and the pawl 85 is in registration with the notch 87 30 and therefore hangs vertically. Any movement of the ratchet segment will throw the pawl into an inclined position for co-action with the ratchet teeth but as soon as the ratchet segment has been carried to its full forward position, the nose of the pawl will enter the notch 88 and again hang in a vertical position, as in Fig. 7. Now as the driving element is returned by the spring actuated operating shaft, the pawl will ride over the ratchet teeth until it again 40 enters the notch 87.

Each segment 83 of a driving element 82 carries an arcuate pusher 89 which is secured to its segment at or near the rear thereof and extends forwardly in an arc having the operating shaft 45 as its axis. This major part of this pusher is spaced from the inside face of its segment and may be considered free. The pusher is positioned so that it may enter holes 90 and 91 in the rear and forward plates respectively of the 50 coin retainer 73, Figs. 13 and 14, which holes form a passageway intersecting the coin recess 75.

If the operating handle is actuated, and there is no coin in the coin retainer, the pusher will 55 pass through the holes without effecting the delivery mechanism, but if a coin is in the coin retainer, said pusher will engage the coin and, in effect, clutch the driving element and its associated idler pinion together. This will cause 60 said idler pinion to run the gear rack, with which it is in mesh outward, and open the closure plug on the support carried by such gear rack.

In order to prevent the gear rack and its 65 associated or component parts from being returned prematurely, a pawl 92 is provided for co-operation with said gear rack. This pawl 92 is pivoted in a pawl bearing 93 secured to the supporting plate 49 and said pawl has a 70 tail 94 in the path of travel of the release arm 95 carried by the flat segment of the driving element.

When the release arm 95 is disengaged from the tail 94 of the pawl 92, as in Fig. 7, the nose 75

of said pawl will contact the teeth of the gear rack and prevent it from being given a retrograde movement by the spring check 51, but when the release arm 85 strikes the tail of said pawl 92, because of the reverse movement of the driving element, said pawl 92 will be disengaged from the teeth of the gear rack, as in Fig. 4, freeing said rack so that it will be returned by the spring check 51.

10 A coin pocket 96 is supported by a bracket 97 secured to the supporting plate 49, with the outlet end of said pocket in alignment with and just above the entrance to the coin recess in the coin retainer 73 when the parts are in the closed position. In order to properly align the coin retainer 73 with the coin pocket 96, an adjustable stop 98 is provided which may be in the form of a screw in the path of rearward or inward travel of the gear rack, and said screw is threaded through an ear 99 secured directly to the supporting plate 49 or indirectly by fastening it to the gear rack guide 61. The adjustable stop 98 impinges against the rear end of the gear rack when the latter is in its innermost position so that when said gear rack comes to rest the coin retainer 73 should be in alignment with the coin pocket 96. If these parts are not in alignment, the adjustable stop 98 is regulated until the coin retainer is aligned 20 with the coin pocket through the longitudinal movement of the gear rack.

15 Leading to each coin pocket is a coin chute 100 supported by the door 23 and to which leads a coin slot 101 formed in said door. It will be obvious from the foregoing description that any number of coins may be inserted in a coin chute but they will only enter the coin retainer one at a time and since a portion of the coin which is in the coin retainer will be flush with the upper outer edges of the retainer plates, the additional coins will be held out of the coin recess and cannot interfere with the functions of the machine. As the delivery mechanism is actuated, the flange 81 on the idler pinion will 30 pass beneath the coin pocket and retain any coins in said coin pocket or the chute until the mechanism has been operated for the delivery of a package of merchandise and the coin in the coin retainer released therefrom. When 35 coin retainer again aligns with the pocket another coin may pass from said pocket into the retainer and the mechanism may again be operated.

20 A coin box 102 is associated with each coin chute, pocket and retainer and is fastened to supporting strips 103 disposed in vertical parallelism across the doorway and the bottom thereof coincides with a coin return opening 104 in the door 23. This coin box has a curved back wall 105 terminating short of the inclined bottom wall and a removable secondary bottom 106 having its inner end terminating short of said back wall thereby leaving a space between them. The secondary bottom is fashioned with a foot 25 107 at its inner end to elevate said inner end sufficiently to provide inclination that will cause coins striking the same to slide to the return opening. The foot has a toe 108 which enters an aperture formed in the bottom wall of the 30 coin box to position the inner end of the secondary bottom in the desired location and the forward end of said secondary bottom engages in a channel rail 109 on the inside of the cabinet front wall below the door way.

25 Between the adjacent ends of the back wall

105 of the coin box and the secondary bottom 106, or within the space between them, is mounted an oscillating return or shunting flap 110 fixed to a crank 111 journalled in the side walls of said coin box. When the flap is turned 5 into one position the coins will enter the box and can be removed after taking out the secondary bottom but when said flap is turned into its other position the coins will be shunted onto the secondary bottom for return to the prospective 10 customer. The operations of the oscillating flap are controlled by the delivery or non-delivery of a package, as will be described.

A package delivery chute 112 having a suitable inclination is attached to certain of the vertical 15 supporting strips 103 and bridges the space between each outlet opening 29 at the bottom of each package container and its respective access opening 113 in the removable door 23. One end of this package delivery chute rests on the 20 sloping sill 30 of the outlet 109. Said other end is fashioned to provide a package stop 114 adjacent the access opening to prevent the delivered package accidentally falling from the machine. On the inclined bottom of said package delivery chute are mounted skids 115 of "Bakelite" or similar substance to prevent the frozen merchandise package from adhering to said delivery chute.

Near the upper end of the package delivery 30 chute 112 is a swinging barrier 116 which may be a solid piece of material or fingers as shown, and this barrier is attached to an axle 117 journalled in the side walls of said delivery chute with a lever arm 118 on one end. To the outer 35 end of said lever arm is connected one end of an extensible pitman rod 119 and the other end of said pitman rod is connected to the crank 111 of the shunting flap 110 in the adjacent coin box. The pitman consists of two sections 40 120 and 121 having threaded or other connection with each other whereby the length of the pitman may be adjusted to normally maintain the shunting flap in a position to return a coin so long as the barrier remains across the package 45 delivery chute or in the path of travel of a package in said chute. To normally hold the barrier across the delivery chute a counter weight 122 may be mounted on the pitman rod or other convenient part.

A second barrier 123 depends from a crank shaft 124 and swings across the lower part of the package delivery chute and retards the final delivery of the package until after the complete 50 operation of the machine.

One end of a runner 125 is connected to the crank shaft 124 and the other end of said runner is pivoted to one end of a link 126 while the other end of said link is pivoted to a bracket 127 on the side of the package delivery 60 chute. The link 126 is longer than the throw of the crank shaft so that the rear end of the runner will be elevated sufficiently to engage the gear rack as the latter is moved forward or outward thereby holding the lower barrier 65 against outward swinging movement and the removal of a package until the machine mechanism has returned to a closed position.

The top of the ice bunker 38 is closed by an independent closure 128 of insulating material 70 and the top of each merchandise container is also closed by an independent closure 129 with independent closure 130 for the upper ends of the spaces between the small cans or containers 75 and all of said closures are surmounted by

a secondary closure 131 having a gasket 132 on its inner face for contact with the side insulation to make an airtight joint.

In order to evenly distribute the low temperature about the package containers or in other words so that the temperature at the tops of the containers will be substantially the same as at the bottoms thereof, absorption fins 133 are attached only to the plate 27 and extend from a position adjacent the upper end of the refrigerant bunker downwardly to a point approximately half way of the height of the bunker and within the spaces between the small cans or package containers or compartments.

While the machine may be used to dispense packages from a single stack, it is particularly designed for selectively vending packages from a plurality of stacks. This is especially advantageous in the dispensing of ice cream or similar frozen products as it enables the owner of the machine to place packages of merchandise of various flavors before prospective customers who may choose the kind desired.

The operation of a multiple unit such as described herein, is as follows:—

Assuming that all of the parts are in the closed position, that is the several constituents of the machine are in the positions taken when the closure plugs are closed or in their respective outlet openings at the lower ends of the package containers or compartments, and said compartments are filled with packages 134 to be dispensed, then upon insertion of a coin in a selected coin slot, said coin will pass through the coin chute and coin pocket into the coin retainer. Now, upon actuation of the operating handle, the operating shaft will be rotated against the action of the spring 46, Fig. 3, until the pusher 89 of the driving element engages the coin in the retainer as illustrated in Fig. 7.

The continued rotation of the operating shaft will cause the driving element to rotate the idler pinion, to which the coin retainer is attached, against the tension of the spring 59 of the spring check 51. This will slide the gear rack 60 forward or outward and remove the closure plug 63 associated with such gear rack, from the outlet opening and simultaneously the package extractor 64 will pull the lower package in the container therefrom and eject it into the package delivery chute.

During these operations, the pawl 85 co-acts with the ratchet teeth 84 on one of the segments 83 to prevent reverse movement of the operating shaft and component parts until the operating handle is moved a complete forward stroke at which time said pawl 85 is released and when pressure on the operating handle is relieved the spring will return the operating shaft and its component parts to the normal inoperative position. This will free the coin and permit it to fall from the coin retainer. Also during the aforementioned opening or dispensing operations, the pawl 92 co-acts with the gear rack 60 to prevent a reverse movement of said gear rack and the parts carried by and associated with such gear rack until the release arm 95 on the segment 83 of the driving element strikes the tail 94 of said pawl 92. This will disengage the pawl 92 and permit the gear rack, with its component parts, to be returned to their normal closed positions by the spring check 51 through the medium of the idler pinion.

By this arrangement there is a certain elapsed

time between the return of the operating handle and the closing of the package container which is sufficient to permit the dispensed package to drop clear of the closure plug into the delivery chute. While there is an appreciable elapsed time between the return of the operating handle and the closing of the closure plug, it is brief enough to permit the delivered package to strike the upper barrier and shift the shunt flap 110 to a position that will direct the released coin 10 into the coin box. If no package is delivered the upper barrier 116 will not be moved and the shunt flap will remain in a position to direct the released coin onto the secondary bottom 106 for return to the prospective customer, such coin being removable through one of the return openings 104.

After the package passes the upper barrier it strikes against the lower barrier 123 and is temporarily arrested in its travel through the delivery chute. This is so because the gear rack is in engagement with the runner 125 which prevents the lower barrier from swinging outward. Upon the return of the gear rack, so that the closure plug is in its closed position, the runner will be released and the weight of the package against the lower barrier will swing the latter and permit said package to descend to the access opening 113 for removal by the customer.

If the operating handle is actuated without a coin in the coin retainer, the driving element will be moved, but the pusher 89 will pass through the holes 90 and 91 in the coin retainer without effecting the delivery mechanism and the machine will not function.

Should any of the vapor or gas, from any cause whatsoever enter the package containers, or any one of them, and create a damaging pressure therein, the package holding rack or racks will be lifted sufficiently to open the hole or holes in the bottom of the small can or cans and the vapor or gas will enter the large can, and if the pressure is still high, it can blow open one or more of the closure plugs against the action of the spring checks and enter the body of the cabinet from which it may readily escape through the joints about the front door 23 or other openings.

Because of the circulating passageways beneath and at both sides and the back of the small cans, formed by the spacing of the walls of the small cans from the walls of the large can and the spacing of said small cans relative to each other, the warmer air at the bottom of said circulating passageways will rise to the top thereof, where the refrigerant bunker is located, to be chilled. This arrangement insures that the package containers will be substantially the same temperature throughout. Any change of temperatures between the upper and lower ends of the containers will be regulated by the shields 41.

Of course I do not wish to be limited to the exact details of construction herein shown and described, as these may be varied within the limits of the appended claims without departing from the spirit of my invention.

Having thus fully described my invention, what I claim as new and useful is:—

1. In a coin controlled vending machine, a container adapted to receive packages to be dispensed, said container having an outlet opening in the front wall at the bottom thereof, a closure plug for said outlet opening, a package

extractor carried by said closure plug for engagement with the rear of a package to propel such package forward through the outlet opening as the closure plug is withdrawn from said outlet opening, a slidably mounted gear rack, means to support said closure plug on said gear rack, coin conveying means, an operating shaft, an idler pinion journaled on said shaft and meshing with the gear rack, a coin retainer carried by said pinion and normally disposed below the discharge end of the coin conveying means, and means fixed to said shaft and operative through the medium of a coin in the retainer to actuate the pinion and thereby move the gear rack to open the closure plug and eject a package.

2. The structure set forth in claim 1, in combination with means to temporarily prevent retrograde movement of the gear rack and hold it in a projected position, means to retract said gear rack when the holding means is released, means to prevent reverse movement of the pinion actuating means prior to a complete forward stroke of said pinion actuating means, means urging the pinion actuating means in a reverse direction, and means on the pinion actuating means to release the gear rack holding means at the end of the reverse movement of said pinion actuating means to permit the gear rack to be subsequently retracted.

3. In a coin controlled vending machine, a package compartment having an outlet opening at the lower end thereof and adapted to con-

tain packages to be dispensed, a closure plug for the outlet opening, means carried by the closure plug and projectable through the outlet opening to extract a package, mechanism operable upon the insertion of a coin for opening the closure plug and actuating the package extracting means, a package delivery chute disposed beneath the outlet opening, a coin box having a coin receiving compartment and a coin return means therein, a coin shunting flap 10 swingingly mounted in the coin box to direct a coin to the coin receiving compartment or the return means, a barrier swingingly mounted in the package delivery chute to be actuated by a package in said package delivery chute, and 15 means connecting the barrier with the coin shunting flap for swinging the latter when said barrier is actuated, said connecting means including a weight to normally maintain the barrier in the path of travel of a package and the 20 shunting flap in a position to direct a coin to the return means.

4. The structure in claim 3, in combination with a second barrier swingingly mounted in the package delivery chute below the first mentioned barrier, and a runner connected with said second barrier and in the path of travel of a portion of the closure plug operating mechanism to hold said second barrier in the path of travel of a package through the package delivery chute to arrest the travel of said package while the closure plug is open.

CHARLES J. PORTER.
